UNITED STATES PATENT OFFICE.

JAMES R. WYATT, OF PHILADELPHIA, PENNSYLVANIA, ASSIGNOR TO THE AJAX METAL COMPANY, INCORPORATED, OF PHILADELPHIA, PENNSYLVANIA, A CORPORATION OF PENNSYLVANIA.

ELECTRICAL INDUCTION-FURNACE.

1,235,629.

Specification of Letters Patent.

Patented Aug. 3, 1917.

Application filed July 19, 1916. Serial No. 119,203.

To all whom it may concern:

Be it known that I, JAMES R. WYATT, a citizen of the United States, residing at 2024 S. 21st St., Philadelphia, in the county of 5 Philadelphia and State of Pennsylvania, have invented a certain new and useful Electrical Induction-Furnace, of which the following is a specification.

The purpose of my invention is to utilize

10 an electric conductor of the first class for the channel walls forming part of the secondary of a transformer, in order to facilitate the melting and maintaining in melted condition of metals whose character prevents 15 their advantageous use as complete secondaries for the transformers, adding the heating effect of the channel walls to that within the channel content.

A further purpose of my invention is to 20 provide electric melting appliances suitable for melting, refining or maintaining in molten condition metals having a relatively low melting point.

A further purpose of my invention is to 25 discharge hotter molten metal along outside channel walls into opposite sides or spaced points of a molten bath in directions initially toward each other, withdrawing cooler molten metal along the inside channel wall 30 at substantially the same points and maintaining a double circulation thereby.

A further purpose of my invention is to 35 utilize an acute angle outside of the pool and preferably obtuse angles at the connection of the channel with the pool in the stirring of a pool having the same level as the molten metal in the channel.

Further purposes will appear in the specification and claims hereof.

40 I have preferred to illustrate my invention by but a few of the forms of the invention to which it may appear, selecting forms which are practical, efficient and which at the same time well illustrate the 45 principles of my invention.

Figure 1 is a side elevation of one form of my invention.

Fig. 2 is a horizontal section upon line 2—2 of Fig. 1.

50 Fig. 3 is a section upon line 3—3 in Fig. 1.

Fig. 4 is a fragmentary enlarged horizontal section of another form.

Fig. 5 is a top plan view of another form of my invention.

Fig. 6 is a section upon line 6—6 of Fig. 5.

Figs. 7 and 8 are a top plan view and section thereof upon line 8—8 showing another form of my invention.

Fig. 9 is a side elevation, partly broken away, of another form.

In the drawings similar numerals indicate like parts.

The form shown in Figs. 1 to 3 inclusive 65 discloses a furnace 10 having a relatively high pool level and a channel 11 connected therewith, closed at the top and having its connections with the pool preferably at the same height and well below the level of the 70 pool.

The furnace comprises the outer jacket 12 provided with a spout 13, a cap 14 connected therewith by ears 15 and bolts 16 and a top 17 carrying a conical refractory 18 which 75 fits into a corresponding opening in an annular refractory 19 carried by the top. The jacket 12 and the casing 20 are united by flanges 21, 22 and the casing is interrupted by flanges 23 and 24, the several flanges being 80 united by any means such as rivets 25. The interruption of the casing reduces or eliminates flow of secondary current through the casing.

The jacket 12 and casing 20 are lined by a 85 refractory 26 which is crowded in about a form of wood or other suitable material the form being divided into two or more parts, the body and channel parts separating for convenience at about the division line between the furnace body and the channel so 90 that the cementitious lining, preferably of asbestos paste, can be forced in about the channel form before the form for the pool is put in place. The pool form can ordinarily 95 be withdrawn and the channel form can be readily burned out where there is difficulty in withdrawing it. The cementitious lining is then gradually dried out.

I prefer to form the channel horizontal 100 and of an elongated cross section which in its most desirable shape is approximately rectangular and much higher in the sections taken than is its width. This is shown in Fig. 3 where the two channel legs 27 and 105 28 are shown as long narrow rectangles. I

have secured excellent results with a proportion of 3 or $3\frac{1}{2}$ to 1.

The transformer used in the first form illustrated is of shell type shown at 29 and 5 comprises three legs 30, 31 and 32 with a laminated frame and a winding or windings here shown as placed at 33 and 34 upon the outer legs. It is air-cooled by well-known means here represented by the nozzle 35 of 10 any suitable air blast system not shown.

Induced flow of electric current in opposite directions in adjacent channels containing molten metal capable of acting as a conductor results in electrodynamic forces in 15 both molten conductors in directions perpendicular to the lengths of the conductors tending to separate the conductors. These forces vary directly as the products of the currents flowing in the two conductors 20 (which becomes as the square of the current where each carries the same current), and inversely as the distance between the parts of the molten metal affected. Where these conductors are not parallel, as in the present 25 case, the electro-dynamic forces vary in magnitude from one point to another along the lengths of the conductors, because of the differing distances separating them, and cause correspondingly varied hydro-dynamic forces, tending to produce motion of 30 the molten metal parallel to the lengths of the conductors. This application of "motor effect" causes motion of the molten metal and hence circulation, if the molten conductor or "fluid" be free to flow. 35

The motor effect may be intensified by bringing the conductors together into an angle, as it is utilized by me, and becomes most effective with an acute angle, increasing 40 within reasonable limits with the acuteness of the angle, until the advantage of increase of pressure gained by making the angle more acute is offset by the increase of friction. Though Joule effect is also present, 45 the hydro-dynamic pressure due to electrodynamic motor effect is dominant.

The hotter metal is driven out along the outer sides of channels 27 and 28, as indicated by the arrows, Fig. 3 and is replaced 50 by a flow of metal from the pool passing along the inner sides of the same channel sections, heating the pool by the additional heat of the hotter metal withdrawn and stirring the pool by the flow, with a resultant 55 intermingling of the hotter metal with that of the pool and gradual and nearly uniform increase of temperature throughout the pool. A narrow stream of hot metal ejected at considerable speed is much more effective 60 than the same quantity delivered in a larger stream at a lower rate, since the stirring effect and immediate distribution obtained by the higher speed reduces the amount of mixing which must be accomplished by the slower Joule effect. The sav-

ing in time is quite material and the temperature at any given time is much more uniform.

The size and shape of the channel are determined primarily by electrical considerations to obtain a suitable power factor in the transformer by proportioning the length and cross section of the channel to secure the most desirable resistance, but the proportion of height to width of channel section, as in Fig. 3, is determined chiefly by the desirability of having a narrow channel to intensify the effect in the corner, the need of sufficient width to avoid excessive fluid friction and the advantage given by additional height in that the action at the corner is extended through a greater range. In a brass furnace having the channel beneath the pool, a pouring heat of over 200 pounds, and a secondary current of seven or eight 80 thousand amperes, excellent results were obtained with a channel having a length in each leg of approximately 18 inches and a cross section of about $\frac{1}{2} \times 3$ inches. 85

Two great advantages arise from this use 90 of motor effect. At any two points considered along the length of either branch of the channel, the pressure is always greater at the point nearer the angle, resulting in a continuity of outflowing stream which would 95 be difficult to attain otherwise and preventing interruption of this stream by inflowing cooler "fluid." The pressure is greatest in the angle 36 from which the metal is driven forcibly, preventing the overheating which 100 would otherwise be likely to occur at this point.

I find it very desirable to round or otherwise make obtuse the inside edges of the molten conductor where its ends 37, 38 unite 105 with the pool, in order to avoid at these points the motor effect which I desire at 36, as motor effect adjoining the pool would be counter in its direction to that set up at 36 and would reduce the outer flow of heated 110 metal. In all of the figures I have therefore shown the inner contour of the channel where it joins the pool, as rounded at 39, but have shown several contours of the outer side of the pool. Thus, in Figs. 2 and 5 the 115 entire channel curves at the end, giving a rounded outer contour at 40, and directing the two streams of hot metal toward each other in the pool, as indicated by the arrows, whereas, in Fig. 7, the outer wall of the 120 channel merges into the wall of the pool, as at 41. This provides a more sharply defined flow of hot metal into the pool in Figs. 2 and 5 and gives quicker diffusion of the heated metal and lower fluid friction of the 125 cooler metal flowing into the channel in Fig. 7.

In operation, the metal, unless it be a soft metal, such as lead of relatively low melting point, is melted before it is poured into the 130

pool, the current is then turned on and hot metal from the channel is forced out into the pool with interchange of cooler metal from the pool. Additional metal may be 5 added from time to time and reduction from ores may be effected, as in other electric furnaces.

In the form shown in Fig. 1, I have preferred to place the pouring spout on the 10 right hand side because with the spout at the left, the channel construction would occupy the place where the ingot or other molds should be located, requiring that these molds be put in place after tilting of the furnace 15 had begun, an undesirable, but not prohibitive arrangement. With the spout upon the right, as shown, pouring causes interruption of the circuit of the secondary, making it very desirable to interrupt the primary current 20 of the transformer before the molten secondary is interrupted by pouring.

My invention is desirable for use with brass, steel and other metals having relatively high melting point, but can be used 25 with lead and its alloys for tempering, refining, etc.

In the form shown in Figs. 5 and 6, the cross section is nearly the same as that of Fig. 1, but a different form of transformer 30 29' is used. In Figs. 5, 6, 7 and 8 the pool and channel are intended to have the same fluid level, and the channels are shown as open at the tops. I have not considered it necessary to show covers for the pool and 35 channel as these are well known in the art and will differ with the needs of intended use.

In Figs. 5 and 6 I have shown the spout as located at the end and the trunnions at the 40 sides. Here, again, tilting to pour from the spout at the right will reduce the section of the secondary circuit in the channel or break it. Notwithstanding this danger, it is preferable to pour at this side rather than from 45 the corner 36, which would result in dross and other impurities flowing down into the channel. Pouring from the corner or angle 36 is also objectionable, unless the primary current be in the meantime interrupted, for 50 the reason that there would be an opposing flow of molten metal due to the motor effect, and because of the small cross section of the channel.

In the forms shown in Figs. 4, 5, 6 and 9, 55 I use a material for the channel walls 42, 43, which is a conductor of electricity of the first class, in order that the secondary current may be carried by it and the secondary circuit reasonably completed, whether the 60 material in the channel be molten or solid and whatever its capacity for carrying the current. This enables me to maintain a low resistance secondary of substantially uniform resistance, even with materials having 65 poor conductivity.

Preferably the walls of the pool are made of the same material as those of the channel, giving advantages in construction as well as in completion of the electric circuit independently of the material of the pool. 70 Where the walls of the channel at their ends are connected by a wall which is also a conductor, the secondary is completed even when the channel is empty.

It will be evident that a conductor of the 75 first class may be used for furnaces having a great variety of shapes including all of those shown in the present application, and that it will possess advantages for handling materials which themselves form poor secondaries, and will be particularly useful in maintaining baths for tempering purposes. 80

In the form shown in Figs. 7 and 8 the construction resembles that of Figs. 1 to 4 in the use of an outer metallic casing and non-conducting lining, but otherwise more nearly resembles the form of Figs. 5 and 6 in the use of single transformers 29' and an equal level of molten metal in the pool and channels. The channels, however, are two in 85 number, 11, 11' and are shown as located at opposite ends of the pool. The trunnions are located at the ends of the channels and the spout at the side of the pool. In this form, the channel wall is substantially tangent 90 with the interior wall of the pool at the point of entry, 44, giving a slight diffusion of hotter metal at this point before the body of the pool has been reached and giving also a wider opening for cooler ingoing fluid which 95 reduces the fluid friction and cross currents of fluid flow at this point. 100

In the form shown in Fig. 9, a conductor of the first class is used for the channel and pool walls, but the channel 11' lies in substantially vertical planes directly beneath the pool, resembling in this the construction shown in Figs. 1 and 2 of the application 105 from which this is divided.

It will be understood that all of the forms 110 are capable of being cooled by air blast, as indicated in the first form shown, or by other means already known in the art.

It will be evident that the character of 115 material used for the conductor of the first class forming the walls of the channel and pool will depend upon the type of construction used and upon the characteristics of the molten material to be handled and particularly the temperature which is to be attained. Steel or a copper alloy would ordinarily be best adapted to the purposes. The electrical conductivity of the intended secondary circuit would, of course, have to be considered in the selection of the material, 120 as well as in the determination of its thickness, the length of the channel, etc., as is already well understood in the art. The current will divide between the solid and molten conductors and the design must pro- 125 130

portion their current values according to the heating desired in each and the circulation sought in the channel content.

Having thus described my invention, what I claim as new and desire to secure by Letters Patent is:

1. In an induction furnace, a furnace body adapted to contain a pool and walls forming a channel therefor having an acute angle in 10 the channel at a distance from the furnace body and having the outer walls of the channels at the connections between the ends of the channel and the pool converging, in combination with a transformer inducing current in the channel content as a secondary and causing outward flow of content into the pool from each channel toward the other, by reason of motor drive.

2. In an induction furnace, a furnace body 20 adapted to contain a pool, walls forming a closed channel connected with the pool at both ends well below the normal surface of the pool and having at the point of connection well-defined converging directions in 25 combination with a transformer inducing flow in the channel content as a secondary.

3. In an induction furnace, a furnace body containing a pool in combination with walls forming a channel connected at both 30 ends with the pool, said walls comprising an electric conductor of the first class, in combination with a transformer inducing current in the channel walls and channel content as secondary.

35. 4. In an induction furnace, a furnace body containing a pool in combination with walls forming a channel connected at both ends with the pool, said walls having an acute-angled bend at a distance from the furnace 40 and comprising an electric conductor of the first class, in combination with a transformer inducing current in the channel walls and channel content as secondary.

5. In an induction furnace, a furnace body 45 containing a pool in combination with walls forming a channel connected at both ends with the pool, said walls having an acute-angled bend at a distance from the furnace and obtuse-angled at the connection with

the pool and comprising an electric conductor of the first class, in combination with a transformer inducing current in the channel walls and channel content as secondary.

6. In an induction furnace, a furnace body adapted to contain a pool in combination with walls forming a channel having the same fluid level as the level of the pool, connecting with the pool at both ends, said walls comprising a conductor of electricity of the first class, and a transformer inducing current in the channel walls and channel content as a secondary.

7. The method of heating the content of a furnace pool which consists in providing a molten conductor outside of the pool connecting therewith by converging conductor terminals, forming an acute-angled bend in the conductor at a distance from the pool and inducing a current of electricity in the conductor to cause metal heated by the induced current to be also ejected from the channel ends by its action, passing out along the outer sides of the channel, the flow from the two channel ends converging.

8. The method of heating a furnace pool which consists in providing a molten conductor connected with the pool at both ends and in contact longitudinally with a solid electric conductor of the first class and inducing a current of electricity in the molten conductor and solid conductor to heat both of them and cause circulation of the molten conductor into the pool.

9. The method of heating a furnace pool which consists in providing a solid conductor of electricity of tubular form terminating at both ends and a molten conductor occupying the space in the solid conductor and connecting with the pool and simultaneously heating both conductors and causing movement of the molten conductor by passing a current of electricity through the length of both conductors.

JAMES R. WYATT.
